CLAIM

The ornamental design for pet clothing as shown and described.

DESCRIPTION

FIG. 1 is a front, left and bottom side perspective view of a pet clothing showing my new design;

FIG. 2 is a rear, right and top side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion marked '9' of FIG.

1;

FIG. 10 is a side elevation view of the pet clothing of FIG. 1 shown in an assembled state as if worn by a pet; and,

FIG. 11 is another side elevation view thereof.

The long dash-short dash broken lines in FIGS. 1 and 9 represent boundaries for the enlarged detail view shown in FIG. 9 and form no part of the claimed design. The remaining broken lines represent features of the pet clothing that form no part of the claimed design.

1 Claim, 11 Drawing Sheets
